US00D986743S

(12) **United States Design Patent** (10) **Patent No.:** **US D986,743 S**
(45) **Date of Patent:** **** May 23, 2023**

(54) **CONTAINER**

(71) Applicant: **Conopeo, Inc.**, Englewood Cliffs, NJ (US)

(72) Inventors: **Gregory Lalier**, Brookfield, CT (US); **Mary Margaret Sheridan**, Stamford, CT (US); **Daniel Martin**, Naugatuck, CT (US); **Wooyeon Cho**, Trumbull, CT (US); **Heesop Chong**, New York, NY (US); **Mariana Escobar Jimenez**, New York, NY (US); **Michelle C Mak**, New York, NY (US); **Laurent Jean-Marie Hainaut**, New York, NY (US)

(73) Assignee: **Conopeo, Inc.**, Englewood Cliffs, NJ (US)

(**) Term: **15 Years**

(21) Appl. No.: **29/761,168**

(22) Filed: **Dec. 7, 2020**

(51) LOC (14) Cl. **09-01**

(52) U.S. Cl.

USPC **D9/689**; D9/682; D9/691

(58) **Field of Classification Search**

USPC D9/500-505, 529, 547, 548, 549, 550, D9/556, 557, 558, 573, 575, 428, 445, D9/518, 551, 563, 564, 520, 449, 718, D9/724, 754, 686, 688, 690, 682, 684, D9/692, 448, 689, 697, 560, 687, 694, D9/691, 516, 542, 545, 571, 574, 683; D3/203.2; D18/56; D28/85, 58

CPC .. B65D 1/0223; B65D 83/205; B65D 1/0246; A45D 34/045

See application file for complete search history.

(57)

CLAIM

The ornamental design for a container, as shown and described.

DESCRIPTION

FIG. 1 is a perspective view from above and one side;

FIG. 2 is a front elevational view;

FIG. 3 is a rear elevational view;

FIG. 4 is a side elevational view from the left side;

FIG. 5 is an elevational view from the other side;

FIG. 6 is a top plan view; and,

FIG. 7 is a bottom plan view.

The broken lines in the figures illustrate portions of the container that form no part of the claimed design.

1 Claim, 5 Drawing Sheets
